United States Patent

Des. 238,985

Patented Mar. 2, 1976

238,985

ZIPPER OPERATOR

James R. Cloud, Sr., P.O. Box 339,
Barnesville, Ga. 30204

Filed July 26, 1974, Ser. No. 492,299

Term of patent 14 years

Int. Cl. D2—07

U.S. Cl. D2—415

FIG. 1.

FIG. 3.

FIG. 2.

FIG. 4.

FIG. 5.

FIG. 6.

FIG. 1 is a top and side perspective view of a zipper operator showing my new design;

FIG. 2 is an inverted opposite side elevational view thereof on a reduced scale with the elongated pull cord omitted for ease of illustration;

FIG. 3 is a top plan view of FIG. 2;

FIG. 4 is a left end elevational view of FIG. 2;

FIG. 5 is a right end elevational view of FIG. 2.

FIG. 6 is a bottom plan view of FIG. 2.

I claim:

The ornamental design for a zipper operator, as shown and described.
